United States Patent Office

Des. 230,342

Patented Feb. 12, 1974

230,342

FOOD CONTAINER COVER

Paul C. Mallonn, Wooster, Ohio, assignor to Rubbermaid
Incorporated, Wooster, Ohio

Filed Feb. 24, 1972, Ser. No. 229,256

Term of patent 7 years

The portion of the term of the patent subsequent to
Oct. 30, 1987, has been disclaimed

Int. Cl. D7—02

U.S. Cl. D7—131

FIG. 1

FIG. 2

FIG. 3

FIG. 4

FIG. 5

FIG. 1 is a top plan view of a food container cover embodying my new design.

FIG. 2 is a side elevation thereof.

FIG. 3 is a sectional view on line 3—3 of FIG. 1.

FIG. 4 is a plan view of a modification thereof.

FIG. 5 is a bottom plan view thereof.

The cross section of the embodiment of FIG. 4 is the same as that shown in FIG. 3, except for the difference in longitudinal dimension shown by comparison of FIGS. 1 and 4.

I claim:

The ornamental design for a food container cover, as shown and described.
